CLAIM

The ornamental design for an electrical connector, as shown and described.

DESCRIPTION

1.1 is a front perspective view.

1.2 is a rear perspective view.

1.3 is a front perspective view in an open position.

1.4 is a front perspective view in another open position.

1.5 is a rear perspective view in an open position.

1.6 is a rear perspective view in another open position.

The broken lines in the figures illustrate portions of the electrical connector that form no part of the claim.
